AUTOMATIC ANTICLOG SALT SHAKER

Mozel A. Adams, Evangeline, La.

Application July 23, 1948, Serial No. 40,347

2 Claims. (Cl. 222—150)

1

This invention relates to salt and condiment shakers, and particularly to a salt shaker equipped with automatic anti-clogging means.

The main object of my invention is to provide a salt shaker of the indicated character which contains simple means operated automatically upon handling the shaker and effective to eliminate clogging of the discharge outlet thereof.

Another object is to provide such a salt shaker which has an internal anti-clogging member movably guided and cooperating with the discharge opening to maintain the latter free of concretions of salt at all times.

A further object is to have a salt shaker of the mentioned type in which the internal anti-clogging member is not only slidably guided, but resiliently supported in position to be effectively operated upon standing the shaker on a support.

It is also an object of the invention to produce a shaker as outlined which may be made of attractive materials, at low cost, to encourage general distribution and adoption of the shaker.

Other objects and advantages of my invention will appear in further detail as the specification proceeds.

In order to facilitate ready comprehension of this invention for a proper appreciation of the salient features thereof, the invention is illustrated on the accompanying drawing forming part hereof, and in which:

Figure 1 is an elevation of a salt shaker made according to the invention and embodying the same in a practical form;

Figure 2 is a vertical section of the same shaker taken on line 2—2 in Figure 3;

Figure 3 is a transverse section of the salt shaker taken on line 3—3 in Figure 1;

Figure 4 is another elevation similar to Figure 1 showing internal detail by fragmentary removal of parts.

In the various views, the same reference numerals indicate the same parts.

As salt is a staple article of diet universally used, various means have been employed for keeping it available at the table, the most common being by means of different forms of salt shakers. Due to the presence of magnesium salts and others in the common salt on the market, the latter is slightly hygroscopic so as to attract moisture and become caked, with the result that discharge openings of salt shakers soon become clogged with adhering concretions of salt preventing further use of the shaker involved until the openings are cleared and the salt within also

broken up to comminute the same so that it may run freely through the openings.

After duly considering this problem, I have succeeded in evolving an automatic anti-clogging salt shaker which avoids the mentioned disadvantages and fulfills the foregoing objects, as will now be set forth in detail.

Hence, in the practice of my invention, and referring again to the drawing, an automatic, anti-clog salt shaker, generally indicated at 5, primarily includes a hollow cylindrically-shaped body 6 which has a reduced threaded portion 7 at the lower end thereof normally screwed into a base 8 having a corresponding internal threaded portion 9 and an inwardly-directed annular flange 10 upon which is located a resilient rubber or plastic disc 11, the flange 10 having a central circular opening 12 across which the resilient disc 11 is suspended.

Upon the upper end of the shaker body 6 is an internally-threaded portion 13 into which a reduced threaded extending portion 14 of a cap 15 is normally screwed, the roof or top 16 of the cap being rounded to form a dome through which an axial aperture 17 is bored to form a discharge opening for the salt within the shaker. Within the shaker body is an axially-disposed movable rod 18 having a pointed upper end 19 registering with the hole 17, while within the lower end 20 is a grooved or reduced portion 21 upon this rod which projects through and engages with the previously-mentioned resilient disc 11 so that when the suspended portion of the resilient disc 11 is moved up or down, the rod 18 will follow, due to its connection therewith in the groove 21, while the opposite is also true that the rod upon being moved by having the lower end 20 thereof engaged against a support 22 will not only cause the upper pointed end 19 to be thrust up through the hole or aperture 17, but the disc 11 will also follow in movement.

When the lower end 20 of the rod 18 is not supported but simply suspended by its connection to the central portion of disc 11, as when the shaker is held in the hand or otherwise removed from a support, as particularly shown in Figure 4, the rod will by gravity cause the central area of the disc to sag in the opening 12 in flange 10, thereby removing the upper pointed end 19 from the discharge opening 17 in the cap 15.

In order to guide the rod 18 accurately so that even when the point 19 is fully withdrawn from the aperture 17 and then insure that the point will be properly guided into the aperture

again and simultaneously break up concretions of salt that may adhere in the aperture or to the under side of the dome portion 16 at 23, for example, a cross-piece 24 having a pair of end lugs 25, 25 is fixed within the wall of the shaker body 6 intermediate the ends thereof by riveting or screwing the lugs 25 in place, or simply by forcing the cross-piece in position with a stiff frictional fit so that it will certainly remain in place. In the cross-piece 24 is an aperture 26 through which the rod 18 slidably extends and due to its lower connection with the central portion of the disc 11 by its groove 21, as well as the slidable engagement in aperture 26, the upper end 19 will be capable of reciprocating 15 through this aperture for breaking up the salt concretions, as already intimated.

When salt is to be introduced into the shaker, the cap 15 is simply unscrewed and the salt poured in to a point above the middle of the shaker body 6, and the cap then replaced. As soon as the shaker is lifted, the weight of the rod 18, as well as of the salt within the shaker, will tend to cause the suspended central area of the resilient disc 11 to sag, as particularly shown in Figure 4, when the discharge opening 17 will be opened due to the withdrawal of the pointed end 19 of rod 18, and when the shaker is then held more or less in a horizontal position and partly inverted, the salt will issue from the discharge opening 17 to the extent desired. When the shaker is again placed upon a support 22, the lower end 20 of the rod 18 will naturally engage against the support and project the point 19 thereof through the aperture 17, filling it for the time being, so that salt concretions cannot accumulate in the opening, while at all times, due to the smooth condition of the rod which is free from shoulders or projections, the latter will readily slide through the opening 26 in cross-piece 24 serving to guide the rod and retain it in guided central position.

The shaker may be made of plastic, wood, metal or of any suitable material, this referring particularly to the cylindrical hollow body 6, as well as base 8 and cap 15, while the cross-piece 24 may either be of metal or of plastic cemented in place, while the resilient disc 11 is preferably of natural or artificial rubber or resilient plastic, and the rod 18 either of plastic or of metal.

Manifestly, variations may be resorted to and parts and features may be modified or used without others within the scope of the appended claims.

Having now fully described my invention, I claim:

1. A condiment holder, comprising an up-standing container adapted to hold the condiment and having a top provided with an aperture, the container including a bottom having a relatively large opening arranged substantially in vertical alignment with the aperture of the

top, an elastic disc secured to the bottom of the container and extending over the opening therein and having an aperture, and an up-standing rod mounted within the container for reciprocation and having its top end extending into the aperture of the top, the lower end of the rod extending through the aperture of the disc for connecting the rod and disc and below the disc so that it may contact the surface which supports the condiment holder, whereby the top end of the rod is maintained within the aperture of the top, the elastic disc sagging under the weight of the rod when the condiment holder is lifted, the rod thereby being lowered so that its top end passes out of the aperture of the top and its lower end projects below the bottom of the container.

2. A condiment holder, comprising an up-standing tubular body portion adapted to hold the condiment and having a top provided with a central aperture, a detachable bottom for the tubular body portion and having a relatively large central opening arranged substantially in vertical alignment with the aperture of the top, an elastic disc clamped between the lower end of the tubular body portion and detachable bottom and extending over the opening of the bottom, the disc having a small central aperture, an up-standing straight rod arranged within the tubular body portion for reciprocation and having its top end extending into the aperture of the top, the rod having an annular groove near and above its lower end, the lower end of the rod being insertible through the small aperture of the elastic disc, said small aperture closing about the rod within the annular groove thereof for connecting the rod with the disc so that the lower end of the rod extends below the disc for engagement upon the surface which supports the condiment holder, whereby the top of the rod is held within the aperture of the top for closing such aperture, the elastic disc sagging under the weight of the rod when the condiment holder is lifted, the rod thereby being lowered so that its top end will open the aperture of the top and its lower end will project below the detachable bottom, and a fixed guide for the rod and mounted within the tubular body portion.
